US0D1012017S

(12) **United States Design Patent** (10) Patent No.: **US D1,012,017 S**
(45) Date of Patent: ** Jan. 23, 2024

(54) **BATTERY CHARGER**

(71) Applicant: **FDK CORPORATION**, Tokyo (JP)

(72) Inventors: **Takashi Kanou**, Tokyo (JP); **Mika Takayanagi**, Tokyo (JP); **Asuka Takahashi**, Tokyo (JP); **Yasunari Mizoguchi**, Tokyo (JP); **Katsuki Tsuchiya**, Tokyo (JP); **Kenji Kitamura**, Tokyo (JP); **Kunihisa Sekiguchi**, Tokyo (JP); **Kazuta Takeno**, Tokyo (JP)

(73) Assignee: **FDK CORPORATION**, Tokyo (JP)

(**) Term: **15 Years**

(21) Appl. No.: **29/761,824**

(22) Filed: **Dec. 11, 2020**

Related U.S. Application Data

(63) Continuation of application No. 35/506,760, filed on Nov. 12, 2018 (U.S. filing date under 35 U.S.C. 384), and having an international filing date of Nov. 12, 2018, now abandoned.

(30) **Foreign Application Priority Data**

May 16, 2018 (JP) 2018-010727

(57) **CLAIM**

The ornamental design for a battery charger, as shown and described.

DESCRIPTION

FIG. 1 is a perspective view of a battery charger.

FIG. 2 is a front view of the battery charger.

FIG. 3 is a back view of the battery charger.

FIG. 4 is a left view of the battery charger.

FIG. 5 is a right view of the battery charger.

FIG. 6 is a top view of the battery charger; and,

FIG. 7 is a bottom view of the battery charger.

In the drawings, the broken lines are for the purpose of illustrating portions of the battery charger that form no part of the claimed design.

1 Claim, 7 Drawing Sheets
